JOSEPH URSELE SUCHET, OF NUITS-ST.-GEORGES, FRANCE.

MACHINE FOR BINDING CASK HOOPS.

Application filed August 13, 1920. Serial No. 403,317.

To all whom it may concern:

Be it known that I, JOSEPH URSELE SUCHET, a citizen of the French Republic, and residing in Nuits-St.-Georges, Côte d'Or, France, have invented certain new and useful Improvements in and Relating to a Machine for Binding Cask Hoops, of which the following is a complete specification.

10 This invention relates to the binding of cask hoops.

The usual operation of attaching the ends of cask or similar hoops by means of wicker or wire is rather difficult to perform, and 15 requires a long time, and in addition, presents but a relatively weak fastening, since the binding becomes rather quickly broken under the action of shocks or by becoming worn, especially when the same is effected 20 by means of wicker.

One object of this invention is to effect an absolutely rigid binding of the said ends by the aid of metallic clasps which are easily and quickly attached, and contemplates a 25 machine which renders it possible to effect the said binding instantaneously and in a safe way.

Another object of the invention is to provide a machine which is simple in operation 30 and easily controlled, and which is designed for strongly tightening the clasp round the ends to be united, and for applying the retaining clip at the desired point.

The invention consists in securing both 35 ends of the hoop to be united between members of a clasp and to maintain the said clasp itself by means of a clip which is put over the bent ends of the same and prevents them becoming unbent, the said clip being 40 driven into the ends of the hoop in order to form a strong binding.

In the accompanying drawings is illustrated by way of example the method of binding the hoop ends together by a machine 45 designed for performing such binding: In said drawings:

Figure 1 shows the binding clasp.

Figure 2 shows the clip for retaining the said clasps.

50 Figure 3 is a side view of the machine for binding said cask hoops.

Figures 4 and 5 are detail views on an enlarged scale showing in elevation and in plan respectively the shaping carrier here- 55 after more fully referred to which shuts

the clasp round the ends of the hoop to be formed.

Figures 6, 7 and 8 are fragmentary views showing the method of action of the carrier upon the branches of the clasp.

Figure 9 is a fragmentary view of the device for putting a clip into position.

Figure 10 is a sectional elevation showing the joint and fastening means produced by the clasp and clip at the ends of the hoops, 65 and

Figure 11 is an enlarged fragmentary perspective view of a portion of the carrier.

The metallic clasp preferably used may be of the shape shown in Fig. 1 which consists in a metallic blade *a* of convenient width conveniently bent, and presenting in its middle part a reinforced part *a'*. The said middle part of the clasp is adapted to be placed on the external part of the hoop 70 while the branches of the said clasp are to be bent inside said hoop; the parts of such hoop being thus kept in the clasp. The clip *b* is adapted to be placed over the bent branches of the clasp in order to prevent 75 the same from being separated and to thus disengage the parts of the hoop. The said clip has two points *b'*, *b''* which are adapted to enter into the said parts and to secure in a still more efficient manner the fixa- 80 tion of the whole. 85

The putting in place of the said clips, if performed manually, would be a long and expensive operation, so it is preferable to use for this purpose the machine shown by 90 Figure 3, and certain detail parts of which are shown by Figures 4 to 9.

On the base *c* of any shape, are fixed standing uprights *d* of I shaped iron or of any other section, and on which are fixed 95 the several parts of the machine. The said parts comprise on the one hand a bearing *e* for the ends of the hoop to be united, and which encloses and slidably receives the carrier *f* for reciprocation therein, together 100 with the guide or block *n* designed for driving the clip, and the arcuate or concaved tightening or clamping jaw *h*. The bearing *e* is formed by two parallel bars fixed to the uprights, spaced a certain distance apart, 105 and fastened by means of bolts or the like, and maintained by convenient struts *i*. The inner or internal faces of said bars are provided with slides or ribs upon which the carrier *f* is adapted to slide. The latter also 110

comprises, in the constructional form shown (Figures 4 and 5) two strips or side pieces, f' , f'' provided with grooves to receive the guiding ribs of the bearing e and which are 5 maintained at a convenient distance apart by a block j which is formed integral with one of them, namely the strip or side piece f' as shown as well as by their assembling parts, bolts or similar parts. The shaping 10 part of the said carrier comprises on the one hand a movable roller k the axis of which is journaled or harboured in oblique grooves l provided in the strips f' , f'' in the bottom of which it normally rests, and, on 15 the other hand by a rounded fixed shoulder m , rounded at its fore end. The said block j is hollowed out or recessed at the bottom for receiving a slideable or movable guide or block n , the flat head of which may reciprocate in the slot or cranny provided between 20 the block j and the rear face of the shoulder m , and is arranged so as to receive the clip b (Figures 4 and 9). The lower part of the 25 guide n is connected by a link o with the controlling lever p .

The longitudinal displacement of the carrier f in the bearing e is controlled by a hand lever q pivoted at q^3 to the uprights d and on the axis of which is keyed a link q^4 , the prolonged hole or slot of which q^5 engages the pin f^3 which forms a bolt for the strips f' , f'' of the carrier f .

The inverted arcuate or concaved jaw or presser h is so conformed as to come in intimate contact with the clasp a and the hoop upon which it is to be applied. It is carried by a rod r which slides in a guide s solid with the branching arms of the U-shaped support or stirrup s' , fixed to the 35 uprights d of the machine. The said rod r is pivoted to a lever r' pivoted on the other hand to a supporting arm d' solid with the frame of the machine. The lowering of the 40 jaw h is controlled by the operation of the pedal t connected by the rod t' with the lever r' and provided with the counterweight t^2 which normally maintains the jaw h in its 45 upper position.

The binding of cask hoops is obtained by 50 this machine in the following manner:

A clip b is first introduced into the slot or cranny j' provided between the block j and the shoulder m in such a manner that it 55 rests, with its points upright on the upper end or jaw face of the flat jaw or projection n' of the guide n ; the height and arrangement of this cranny is, of course, such that the points of the clip are flush with the upper part of the carrier and are not in the 60 way for the putting in place of the hoop to be bound. The latter is then placed upon the bearing e , on the upper face of which the ends to be united are then surrounded by a clasp a , the branches of which are protruding 65 between the strips of the carrier as may

be seen in Fig. 6. The jaw h is then lowered by pressure exerted on the pedal t and it is maintained firmly pressed against the clasp during the whole operation in order to prevent the hoop and the clasp which it carries 70 from moving or shifting on the bearing e and becoming displaced from the position in which it will be properly acted upon and secured in position. The carrier f at that time occupies its middle position, that is to 75 say that, as shown by Figure 6, in the middle part of its stroke, the controlling lever q being vertical. On throwing the said lever q , thus bringing it into the position q' , the carrier f is caused to glide up 80 to the end of its course in the bearing e . In this movement, the roller k meets with one of the branches of the clasp a (the branch a^2 in the example shown in Fig. 6) 85 the said clasp being maintained fixed by the jaw h , the roller begins bending the branch a^2 while going up under the action of the resistance it is offering to its displacement, to the upper part of the oblique groove l ; it goes on progressing to act upon the branch 90 a^2 until the time when, the carrier having reached the end of its fore stroke, it reaches the upper end of the branch a^2 , bends down the same completely and fastens the same 95 strictly against the internal face of the hoop.

On bringing back the lever q to its rear position, the carrier f is displaced in the opposite direction, and its shoulder m comes into contact with the branch a^3 of the clasp. Under the action of the rounded part of the 100 said shoulder the branch a^3 is progressively bent over the branch a^2 until, the lever q occupying the position q^2 and the carrier being at the end of its rearward stroke, it is 105 firmly maintained by the passage of the shoulder m . At that time, the hoop is placed exactly above the cranny j' which encloses the clip b . It is then sufficient to raise the hand lever p for causing the points of the 110 said clip to enter into the hoop and bring its transverse part or bight portion against the bent parts of the clasp. These several operations, which are very quickly effected to permit the placing of in a very short time 115 as many clasps as it is necessary for insuring the perfect fixation of both the ends of the hoop.

It is quite evident that the described arrangement could be slightly modified, and 120 for instance the controlling parts of that apparatus could be arranged in a different manner, or the shapes of the operating parts could be varied without departing from the spirit of the invention.

Having now particularly described and ascertained the nature of said invention and in what manner the same is to be performed, I declare that what I claim is:

1. A method for connecting or binding the 130

- ends of cask hoops or other similar hoops, consisting in passing a clasp around the ends to be united while maintaining said ends firmly clasped together and then forcing a 5 clip against the ends of said clasp and across and at right angles to said clasp and said ends, said clip being forced into the wood of the hoops and pressed against said ends of the clasp when bent upon each other.
- 10 2. A machine for binding cask hoops comprising a clamping member for holding the ends of the hoops pressed toward each other in assembled relation, means for applying a clasp around said ends, and means cooperating therewith for forcing a clip into the wood of the hoops at the overlapping ends thereof to anchor the clasp in position.
3. A machine for binding and clasping cask hoops comprising a movable carrier, 20 means for supporting the hoops at the ends thereof in overlapping relation and pressed toward each other, said carrier being provided with members which during the displacement of said carrier act upon the 25 branches of the clasp to bend the same against the inner face of the hoop, means for applying the clip, means for displacing the carrier, and means for forcing the ends of the clip into the inner face of the hoop 30 and thus forcing the same into the clasp.
4. A machine of the class described comprising a frame, a bearing carried by the frame, a carrier movable in the bearing and adapted to receive thereon the ends of a 35 hoop to be joined, means for bending the ends of a U-shaped clasp toward each other and against the inner surface of the hoop upon movement of the carrier, and means for forcing a clip in straddling relation to 40 the overlapping bent ends of the clasp and into the overlapping ends of the hoop to secure the clasp in position.
5. A machine of the class described comprising a frame, a bearing carried by the 45 frame, a carrier movable in the bearing and adapted to receive thereon the ends of a
- hoop to be joined, means for clamping the hoop in position and against movement on the bearing and carrier, means for shifting the carrier, means on the carrier for engaging the ends of a clasp fitted around the ends of a hoop to be joined so as to force said ends against the inner surface of the hoop in overlapping relation, and means cooperating with the carrier for forcing a clip into 50 the wood of the hoop at the points thereof and constituting a pushing device for driving said points and fastening the transverse part of the clip against the bent branches of the clasp in order to prevent the same from 55 becoming disengaged.
6. A machine for binding cask hoops, comprising a base, uprights mounted upon the base, a bearing supported in an outstanding position upon the uprights, a carrier 60 adapted to reciprocate in the bearing, means for reciprocating the carrier, means for clamping the overlapping ends of a hoop in assembled relation upon the bearing and over the carrier, said carrier having a slot 65 adapted to receive the ends of a U-shaped clasp engaged over the hoop at the overlapping portions and provided with spaced engaging members to bend the points of the 70 clasp in opposite directions upon reciprocation of the carrier so as to move the same in opposite directions, said carrier being provided with a slot adapted to receive a clip transverse to the position of the clasp and the bent branches thereof, and a pushing 75 device for driving the points of the clip into the wood of the hoop and tightening the transverse part of the clip against the bent branches of the clasp in order to prevent the same becoming disengaged, said device being movable with respect to the carrier and supporting and engaging the clip.
- In testimony whereof I have hereunto set my hand at Paris this day 30th of July, 1920.

JOSEPH URSULE SUCHET.
